UNITED STATES PATENT OFFICE.

JOSEPH DEAN HATHAWAY, OF MONTREAL, QUEBEC, CANADA.

COVER FOR FUSES OF PROJECTILES.

1,313,088.

Specification of Letters Patent.

Patented Aug. 12, 1919.

Application filed May 7, 1917. Serial No. 167,037.

To all whom it may concern:

Be it known that I, JOSEPH DEAN HATHAWAY, a citizen of the United States of America, and resident of the city of Montreal, Province of Quebec, Canada, have invented certain new and useful Improvements in Covers for Fuses of Projectiles, and do hereby declare the following to be a full, clear, and exact description of same.

10 This invention relates to covers which inclose the fuses of projectiles and protect same from injury and dampness during storage and transportation and appertains particularly to the means of attaching such 15 covers to the fuses.

Fuses to which my invention specially applies are of conical form and the covers conform more or less thereto and are each removably attached to the fuse through the 20 medium of a tearing off strip which being soldered to the rim at the base of the cover is, upon the latter being applied to the fuse, soldered thereto to form a sealing bond which is ripped off to release the cover when 25 uncovering the fuse for use.

An object of the invention is to improve the general construction of fuse covers as above with a view to economy of manufacture and facility of application.

30 For full comprehension, however, of my invention reference should be had to the accompanying drawings forming a part of this specification in which similar reference characters indicate the same parts and 35 wherein:

Figure 1 is a perspective of my improved cover;

Fig. 2 is a transverse vertical section of same as applied to a fuse; and

40 Fig. 3 is an elevation of the tearing off strip.

Having reference to the drawings, the fuse cover consists of the hollow metallic cone-like member 2 and a metallic tearing 45 off strip 3 soldered thereto.

As heretofore constructed the cover has been inclined continuously from the apex to the rim, so to apply and solder a flat tearing off strip of sheet form flat upon the rim of 50 such a cover the strip had to be fashioned in the curved form indicated by dotted lines Fig. 3 to compensate for the varying diameters of the inclined wall of the cover. This necessity prevented economical cutting or stamping of the blanks from which the strips are 55 made as considerably more scrap is left af-

ter forming curved strips than uncurved ones.

For this reason and another which will be hereinafter pointed out, I have constructed 60 the cone 2 with a wall which flares downwardly from the apex to a point 4 and continues to the rim in a line substantially parallel to the axial line of the fuse to be covered thus forming a substantially non- 65 inclined base 5. The tearing off strip is soldered at 6 to and forms a substantially parallel continuation of this base and as the latter is not inclined but presents an approximately constant diameter a strip which 70 as shown in full lines Fig. 3 is straight or uncurved before application can be soldered flat thereon.

The cone with the tearing off strip attached is placed over the fuse as shown in 75 Fig. 2 and sealed thereon by soldering the strip 3 to the fuse all around same thus insuring the exclusion of moisture which deteriorates the fuse.

The tearing off strip is of a length to 80 extend completely around the base of the cone and overlap so that it can be soldered to completely surround the base and leave an end which overlapping the strip is soldered thereto for a portion 8 of its length 85 and terminates in a free end 9 by which the strip may be grasped and through the purchase thus obtained ripped off from cone and fuse and free the former. Before removal, the free end of the strip is confined 90 beneath a keeper consisting of a finger 10 secured at one end to the cone by a drop of solder and bent down over said free end.

The above described strip confining means 95 may be modified as desired as other and well known means may be employed, the main requirement being the arrangement whereby the separate releasing strip can be torn off and so distinguishing especially from certain prior arrangements in which the cone 100 itself is torn to release same. Therefore in comparison with the tearable one, the cone 2 can be made from substantial and practically untearable metal of sufficient tensile strength to sustain considerable shock without bending and so more efficiently protect the fuse against physical injury as well as excluding moisture.

This last mentioned feature is not new in 110 itself but those covers heretofore known have presented the above described disadvantage of being inclined from apex to rim and have

the additional objection of either necessitating the attachment of the tearing off strip thereto after being placed over the fuse or of being merely soldered to the inclined fuse 5 body without additional support to augment the solder bond so that the latter will stand up under strain in a manner commensurate with the strain resisting qualities of the cone. The advantages of the strong covering 10 cone is augmented by the described bases as the strain due to impact is transmitted by the latter in the axial line instead of obliquely but in order to still further add to the strength of the cover without sacrifice of the advantage of applying both cone and strip as one member, I make a circumferential groove in the inclined surface of the base of the fuse and thus form an annular projecting shoulder 12 upon which the 15 lower edge of the tearing off strip rests and is soldered in such position to the exterior of the fuse at 13. The shoulder 12 forms an abutment for the cover and, assisted by the transmission of the strain in the axial line 20 through the base sustains what may be termed the end thrust of the latter and relieves the solder bond between fuse and cover from practically all strain due to impact upon the cover and which might tend to 25 break the bond. Furthermore the provision of shoulder 12 and tearing-off strip upon the base of the described construction enables the solder connection between strip and fuse to be applied to the exterior of both 30

fuse and strip thus providing for easy access 35 to the actual parts to be soldered and thereby facilitating this soldering operation.

What I claim is as follows:

1. In combination, a cone-like fuse having a projecting annular shoulder near its base, 40 and a cover adapted to be placed over the fuse; said cover consisting of a hollow member in the form of a cone with a cylindrical base portion, and a tearing-off strip encircling said cylindrical base portion and having 45 one of its longitudinal margins soldered thereto, the edge of its opposite longitudinal margin resting upon the shoulder of the fuse and being soldered thereto and such strip also presenting a free end portion. 50

2. In combination, a cone-like fuse having a projecting annular shoulder near its base, and a cover adapted to be placed over the fuse; said cover consisting of a hollow member in the form of a cone with a cylindrical 55 base portion, a tearing-off strip encircling said cylindrical base portion and having one of its longitudinal margins soldered thereto, the edge of its opposite longitudinal margin resting upon the shoulder of the fuse and 60 being soldered thereto and such strip also presenting a free end portion, and a keeper soldered to the exterior of the cone near the upper edge of said tearing-off strip for retaining the free end of such strip. 65

In testimony whereof, I have signed my name to this specification.

JOSEPH DEAN HATHAWAY.
